(57) **CLAIM**

The ornamental design for an inserter jaw for a prosthesis impaction and extraction tool, as shown and described.

DESCRIPTION

FIG. 1 is a perspective view of an inserter jaw for a prosthesis impaction and extraction tool shown in an environment illustrating our new design;

FIG. 2 is a top plan view of the inserter jaw for a prosthesis impaction and extraction tool shown removed from a portion of its environment in order to show aspects of the design that are not apparent in the perspective view;

FIG. 3 is a bottom plan view thereof;

FIG. 4 is a left side elevation view thereof;

FIG. 5 is a right side elevation view thereof;

FIG. 6 is a rear end elevation view thereof, it being understood that the inserter jaw is not visible in the rear end elevation view;

FIG. 7 is a front end elevation view thereof; and,

FIG. 8 is an enlarged perspective view thereof shown in an environment.

The evenly spaced broken lines shown that are immediately adjacent the shaded areas represent unclaimed boundaries while the remaining evenly spaced broken lines and the dot-dash broken lines are directed to environment and are for illustrative purposes only; the broken lines form no part of the claimed design.
